Primary Examiner — Janice Hallmark

(57) **CLAIM**

The ornamental design for a phone holder, as shown and described.

DESCRIPTION

FIG. 1 shows a front perspective view of a phone holder in accordance with the present invention;

FIG. 2 shows a rear perspective view thereof;

FIG. 3 shows a top view thereof;

FIG. 4 shows a bottom view thereof;

FIG. 5 shows a front view thereof;

FIG. 6 shows a rear view thereof;

FIG. 7 shows a right side view thereof; and,

FIG. 8 shows a left side view thereof.

The broken lines shown in the drawings represent environmental subject matter and do not form any part of the claimed design.

1 Claim, 6 Drawing Sheets
